(57) **CLAIM**

The ornamental design for a display screen or a portion thereof with a graphical user interface, as shown and described.

DESCRIPTION

The FIGURE is a front view of an image of a display screen or a portion thereof with a graphical user interface, showing our new design.

The outer perimeter broken lines shown in the FIGURE depict a display screen or a portion thereof and form no part of the claimed design. The remaining broken lines in the FIGURE depict portions of a graphical user interface and form no part of the claimed design.

1 Claim, 1 Drawing Sheet
